UNITED STATES PATENT OFFICE.

CLARENCE E. REED, OF WICHITA, KANSAS.

ROTARY DEEP-WELL BORING AND CORING APPARATUS.

Application filed April 9, 1926. Serial No. 100,920.

This invention relates to rotary deep well boring and coring apparatus.

It is common practice in rotary wells of 3,000 to 4,000 feet depth and 10 inches or 5 11 inches in diameter, to use a hollow pipe drill stem, of either 5 inches or 6 inches in diameter, and experience has shown that in deep wells in so-called hard earth formation, the heretofore known core bits have 10 sufficient lateral movement, due to the great depth and the flexibility of the drill stem to wobble in the hole they make enough to reduce the diameter of the core, if any, left standing so much that core lifting devices 15 will not recover the core. In 11 inch cutting diameter bits, not infrequently the core is reduced three-fourths of an inch by bits whose inner cutting edges are spaced apart on a diameter of three to three and one-half 20 inches.

One object of this invention is to provide means in a coring bit for recovering the cores under such conditions.

Some coring bits known and used in the 25 rotary drilling trade have employed a sleeve, with cutting edge, projecting below the plane of the main cutters grouped or spaced about the mouth of the core barrel, and these are successively used in so-called soft earth 30 formations where the penetration of the strata by the tool is rapid under the weight imposed. But where the formation is hard enough to slow up the penetration of the strata by the tool, the bit grinds about, wobbling in its own hole enough to destroy the core or reduce the diameter of the core so 35 much that the core lifters within the core bit cannot obtain hold enough to recover the core, if one is left standing. Such bits employing sleeves have a cutting edge to trim the core to the diameter of the mouth of the bore, or less. The cutting edge of such sleeves are of very limited life and of no 40 value for coring hard formation.

45 This invention eliminates the destructive effect of the wobble on the core that tends to rise at center of the hole, and also eliminates the friction that such sleeves or their equivalent set up. This friction is known 50 to be so great in blade or scrape type cutters, that the friction sometimes fuses even the metal and often burns the core to a slag, making worthless the sample of the formation recovered.

55 In addition to the broader objects of this invention, there are details of construction

whereby an efficient and durable structure is obtained for rapidly penetrating the so-called hard formations and means for delivery of circulation fluid are provided with the opening so placed that the cuttings are carried away without washing the core.

These, and other objects and advantages, will more clearly appear from the description of my invention which is illustrated in the accompanying drawings, in which:

Fig. 1 is a bottom plan view looking upward at the lower end of the head, with rotary cutters in place.

Fig. 2 is a sectional view of Fig. 1 on line 2—2 thereof.

Referring more particularly to the drawings, 1 indicates the annular head of the apparatus which is threaded at its upper end for connection to the usual hollow pipe drill stem, serving to rotate the head and through which circulating fluid is supplied to flush out the bore hole. Within the annular head threads are provided to receive the lower 80 end of a tube (not shown), which tube receives and protects the core from the flushing fluid in the usual manner. Below the threads within the bore is shown an annular core lifter 2 with grips 2¹ and 2².

Rotary cutters 3 and 4 make an annular 85 groove around a core which tends to rise at the center of the bore hole.

5 is the mouth of the core barrel.

6 indicates the metal of the bit head projecting downward surrounding the mouth 90 5 of the core barrel and occupying the space between the radius of the bore of the head and the inner edge 7 of the cutter 4. Heretofore, it has been thought necessary and all core barrels known to the trade have been 95 built with the inner cutting edge in line with the bore or over-lapping the same.

One of the primary objects of this invention is to provide an apparatus which will make hole as rapidly as possible in hard 100 formation, in which the bit wobbles in its own hole. The arrangement of metal of the bit head as shown at 6, compensates for the wobble of the head and prevents the inner cutting edge 7 from reducing the diameter 105 of the core so much that the core lifters cannot obtain a grip. There is no way to prevent the wobble of the head. This invention compensates for the wobble. The mouth of the core barrel being in a horizontal plane substantially the same as the root of the teeth on the cutter, permits the

cutter to disintegrate the material in an annular path at the bottom of the bore hole without bringing the metal of the bit head at 6 into friction contact with the bottom of the bore hole. Where sleeves, such as new commonly used, are employed, the sleeves extend below the plane of the cutters describing an annular path about the core, and have heavy friction contact with the bottom of the hole. Such sleeves are universally provided either with a cutting edge or cutting teeth, and have for their main object the taking of a sample in advance of the main cutting plane in order that a core may be obtained without being washed by the circulating fluid.

In this invention, the circulating fluid will pass through the head between the core tube and the wall of the bore, and from the said annular space will pass downward through passages 8. As clearly shown in the drawings, these passages 8 extend downwardly and outwardly and open adjacent the cutters at a point near the upper portion of the cutters and at the periphery of the head so that the fluid, upon exit, starts upward in the well without impinging at the bottom of the hole.

This arrangement further assists in taking an uncontaminated sample of the bottom of the hole by the distribution of the circulation fluid and the outlets provide a very efficient means of washing the cutters in sticky formations and prevent sticking 35 the apparatus in the bore hole.

4^a are teeth on the rotary cutter 4. 4^b is a removable bearing and retaining member on the portion of the bit head 1^a supporting the cutter 4.

Having thus described the preferred form of my invention, I do not wish it to be understood that my invention is limited to the exact, detailed description and illustrations, since it is obvious that changes may be made therein without departing from the spirit of the invention, as for instance: blade type cutters may be used in the formations to which they are adapted instead of the rotary cutters shown, the inner edge of the blade type cutter being spaced further from the longitudinal axis of the head than the diameter of the bore therethrough, the mouth of the bore being in substantially the same horizontal plane.

What I claim is:

1. In combination in a rotary deep well core bit, a head having a bore to receive the core, core lifting means, cutting means for penetrating the earth formation to form a core, the cutting edges of which means are spaced further away from the vertical axis of the head than the radius of the bore therein, said head having a non-cutting plain surface area surrounding the mouth of the bore, intermediate said bore and the inner

edge of the cutting means, and extending in substantially the same horizontal plane in which the adjacent portion of the cutting means lies, substantially as described.

2. Apparatus according to claim 1 in which said non-cutting plain surface area is in substantially the same horizontal plane as the root of the teeth of the innermost edge of the cutter, said plain surface area completely surrounding the core bore. 75

3. Apparatus according to claim 1 in which the cutting means consists of rotary cutters and the head is provided with flushing fluid passages extending through the head and opening adjacent the cutters. 80

4. Apparatus according to claim 1, in which the said narrow non-cutting area is in a horizontal plane above the plane of the cutting teeth, but substantially no higher than the root of the said cutting teeth. 85

5. In combination in a rotary deep well coring apparatus, an annular head, rotary cutters spaced about the outside of one end of the head in pockets that incline upwardly and inwardly, and another pocket in the same end to receive a cutter whose axis is in a plane at right angles to the longitudinal axis of the head, the said cutter being carried by a spindle integral with and projecting outwardly from a body portion surrounding the bore through the head, said body portion from which the integral spindle projects presenting a non-cutting plain surface area surrounding the mouth of the bore and intermediate said bore and the inner edge of the cutter on said spindle, said plain surface extending in substantially the same horizontal plane in which the adjacent portion of the said cutter lies, substantially as described. 95

6. In combination in a rotary deep well drilling bit, a head, rotary cutters spaced about the outside of one end of the head, the axes of the cutters inclining downward and inward, and another cutter in the same end whose axis is in a plane radial to the longitudinal axis of the head, the said cutter being carried on a spindle integral with and projecting outward from the body metal surrounding the longitudinal axis of the head, said spindle being below a plane intersecting the axes of the first mentioned cutters at the periphery of bit head, the cutter on the said spindle trimming the core that tends to rise at the center of the hole, 110 said body portion from which the integral spindle projects presenting a non-cutting plain surface area surrounding the mouth of the bore and intermediate said bore and the inner edge of the cutter on said spindle, said plain surface extending in substantially the same horizontal plane in which the adjacent portion of the said cutter lies, substantially as described. 115

7. In combination in a rotary deep well 120

- drilling bit, a head, rotary cutters spaced about the outer portion of one end of the head, the axes of the cutters inclining downward and inward, the tooth edges of cutters 5 making an annular groove about the bottom of the bore hole, another cutter in the same end, a spindle for said last named cutter integral with and projecting outward from the body metal surrounding the longitudinal axis of the head, the axis of said spindle being in a plane radial to the longitudinal axis of the head and below a plane intersecting the axes of the first mentioned cutters at the periphery of the bit head, the 10 cutter making clearance for the inner bearing 15
- ings of the first mentioned cutters, the innermost cutting edges trimming the core that tends to rise at the center of the hole, said edges not overlapping the bore of bit head. 20
8. Apparatus according to claim 1 in which the cutting means includes a rotary cutter member and the head has a horizontal spindle integral with and extending outwardly from the wall of the head surrounding the bore and rising from the said non-cutting narrow plain surface area. 25

In testimony whereof, I affix my signature.

CLARENCE E. REED.
